UNITED STATES PATENT OFFICE.

RUFUS A. PARENT, OF SOUTH TACOMA, WASHINGTON.

AUTOMATIC INSULATOR.

1,212,547.

Specification of Letters Patent. Patented Jan. 16, 1917.

Application filed May 23, 1916. Serial No. 99,361.

To all whom it may concern:

Be it known that I, RUFUS A. PARENT, a citizen of the United States of America, residing at South Tacoma, in the county of Pierce and State of Washington, have invented certain new and useful Improvements in Automatic Insulators, of which the following is a specification, reference being had therein to the accompanying drawing.

10 This invention relates to an automatic insulator which is so constructed that after a wire has been drawn to a taut position between the blocks it may then be moved downwardly so as to become wedged between the blocks and thus be retained against sagging or slipping.

Another object of this invention is the production of an insulator which has a plurality of blocks so as to be of a divided construction although there is provided a plurality of wedging ribs formed so as to provide an enlarged entrance opening into which the wire may be passed so as to be moved downwardly between the ribs and thus be wedged between the ribs to be held in a taut position.

Another object of this invention is the production of a divided insulator wherein a frame is provided for detachably supporting the blocks in such a manner as to positively and efficiently hold the same in a position to grip the wire, thereby preventing their accidental displacement.

With these and other objects in view this invention consists of certain novel combinations, constructions, and arrangements of parts as will be hereinafter fully described and claimed.

In the accompanying drawing:—Figure 1 is a side elevation of the automatic insulator as constructed in accordance with this invention. Fig. 2 is a top plan view of the insulator. Fig. 3 is a horizontal section taken on the line 3—3 of Fig. 1. Fig. 4 is a detail perspective view of one of the blocks. Fig. 5 is an elevation of a slightly modified form of supporting frame.

Referring to the accompanying drawing by numerals it will be seen that the supporting frame comprises the base arms 1 which extend in opposite directions. One of the arms has a vertically extending finger 2 which is externally threaded at its upper end as shown at 3. The opposite base arm 1 is provided with a vertically extending finger 4 having an overhanging

lip 5. It will be seen that the two arms 1 are formed integral upon and extend from the screw 6. This frame is adapted to be fixedly carried upon the cross-arm of a telegraph or telephone pole by the screwing of the screw 6 into the cross-arm, whereby the frame will be carried in an upright or vertical position.

The two blocks are similarly constructed and, therefore, it is thought that a description of one of the blocks will be sufficient to clearly disclose the construction of both. Each block 7 is elongated and has upon its inner face the wedging rib 8. This rib 8 is reduced at its upper end, although it is broadened at its lower portion and extends for a considerable distance beyond the inner face of the block 7, as shown in Fig. 1. It should be noted, however, that the ends 75 of the block 7 are formed in a plane in the rear of the lower portions of the wedging rib 8 so as to not interfere with the operation of the rib. Upon the outer surface of the block 7, however, there is formed a vertical channel 10 for purposes to be herein-after set forth.

When this automatic insulator is in operation the frame is mounted upon the cross-arm of a pole as above set forth. One block 85 may then be positioned between the vertical fingers 2 and 4 and may be moved back under the lip 5. At this time the finger 4 will be fitting within the vertical channel 10 of the particular block, while the lip 5 will be 90 overhanging the upper surface of the block, thus holding the block from being removed from engagement with the frame. The remaining block 7 may then be positioned so

as to rest upon the opposite base arm 1, 95 while the vertical finger 2 will be resting within the channel 10 of this block. The nut 11 may then be threaded upon the end 3 of the arm 1 until the nut engages the upper surface of the block engaging the finger 2, 100 whereby this block will also be held against accidental displacement. The wire which is being strung may then be drawn tautly across the upper portion of the insulator and then by being moved downwardly between the two blocks it will engage the central wedging ribs 8 which are directly in alinement with each other, as shown in Figs. 1 to 3 inclusive, whereby the wire will wedge between these ribs. This action will hold 105 the wire 12 very positively and prevent the same from sagging or slipping when in use.

By this simple construction it will be seen that the wire may be very quickly placed in engagement with the insulator and because of the simple and durable construction of this insulator the possibility of the same becoming broken or out of order when in use is greatly minimized.

If it is desired to remove the wire the wire may be gripped and then by pulling upwardly upon the wire it will be removed from the binding action of the wedging ribs 8. It will be noted that when the blocks are in engagement with the frame they will be positively held against side movement by the fitting of the fingers 2 and 4 within the vertical channels 10, while they will be held against vertical movement by resting upon the base arms 1 and by the engagement of the lip 5 and the nut 11.

It is, of course, obvious that under some conditions it may be desired to support the insulator upon the side portions of a post or in fact upon various vertically positioned structures. In order to accomplish this function the frame as shown in Fig. 5 is employed. This frame comprises a base 1' having vertical side fingers 2' and 4'. The finger 4' is provided with an overhanging lip 5', while the externally threaded end 3' of the finger 2' is adapted to carry a nut 11'. It is obvious that the blocks used in connection with this frame are the same as used in connection with the preferred form and, therefore, the operation of the insulator is in all respects similar to operation of the preferred form. However, a screw 13 is formed upon the finger 4' so as to extend from the side portions of the frame, whereby the screw may be screwed into a vertical supporting structure, although the frame will be carried in a horizontal position so as to carry the blocks in the same manner they are carried in the preferred form.

From the foregoing description it will be seen that a very efficient, simple, and durable automatic insulator has been provided, wherein the blocks are provided with central wedging ribs so that a wire after being drawn tautly across the upper portion of the insulator may be moved downwardly between the ribs and by the wedging action of the ribs be held in a taut condition. It will further be seen that the construction of the frame is such as to permit the same to be easily carried upon a supporting structure, while the side arms of the frame by fitting within the channels of the blocks will hold the blocks against displacement, together with the assistance of the overhanging lip and the nut as hereinbefore set forth.

It will be noted by referring particularly to Fig. 3 that as the wire 12 is wedged between the central ribs 8 it will normally be held from slipping as hereinbefore stated. If, however, undue strain is brought to bear

in one direction upon the wire, it will cause the two blocks to pivot upon the arms 4 of the supporting frame, swinging the two ends 9 thereof into a clamping engagement with the wire, as shown clearly in dotted lines in Fig. 3, and thus two points of binding action will be exerted upon the wire, namely the central ribs and the two clamping ends of the blocks. It will be seen that in this manner the wire will be efficiently held from slipping and that the blocks may pivot in either direction in accordance with the manner in which the wire is being pulled.

What is claimed is:

1. An insulator of the class described, comprising a plurality of blocks, means for supporting said blocks, wedging ribs formed upon the inner faces of said blocks, said ribs being enlarged at their lower portions and tapering toward their outer portions, thereby providing an enlarged entrance therebetween, whereby a wire may be passed between said ribs until the same becomes wedged, thereby causing the wire to be efficiently supported by said blocks.

2. An insulator of the class described, comprising a plurality of blocks, means for supporting said blocks, said blocks comprising elongated bodies, wedging ribs formed upon the inner faces of said blocks, said wedging ribs having widened enlarged lower portions, said ribs tapering so as to be considerably reduced at their outer ends, thereby providing a widened entrance opening, the ends of said blocks being formed in a plane to the rear of the inner bearing faces of said wedging ribs, whereby a wire may be quickly and easily passed between the outer portions of said ribs and then by being moved inwardly thereon will finally wedge between the ribs and thus be retained by the insulator.

3. An insulator of the class described, comprising a plurality of blocks, said blocks provided with channels in their side portions, a frame supporting said blocks and fitting within said channels, whereby said blocks will be held in engagement with each other, and means carried by said blocks for gripping a wire and automatically holding the same therebetween.

4. An insulator of the class described, comprising a plurality of blocks having vertical channels in their outer side portions, a frame having base arms fitting upon said blocks for supporting the same, vertical fingers extending from said base arms and fitting within said channels, whereby said blocks will be held against side displacement, and means carried by said blocks for engaging a wire and holding the same in engagement with the insulator.

5. An insulator of the class described, comprising a plurality of blocks, said blocks

- having vertical channels in their side portions, a frame comprising base arms, vertical fingers carried by said base arms, means for supporting said frame, said fingers fitting within said channels, whereby said blocks will be efficiently supported, and means for holding said blocks from accidentally moving from engagement with said frame.
- 10 6. An insulator of the class described, comprising a plurality of blocks, said blocks having vertical channels in their side portions, a frame comprising base arms, vertical fingers carried by said base arms, means for supporting said frame, said fingers fitting within said channels, whereby said blocks will be efficiently supported, one of said fingers being provided with an overhanging lip, the remaining finger being provided with an externally threaded extension, a nut carried upon said threaded extension, said lip bearing upon the top of one of said blocks and said nut bearing upon the top of the remaining block, whereby said blocks will be removably held upon said frame, and means carried by said blocks for receiving a wire and holding the same in engagement therewith.
- 15 7. An insulator of the class described, comprising a frame, said frame comprising base arms, fingers extending from said arms, means for supporting said frame, blocks positioned upon said frame, said blocks having channels, said fingers resting within said channels, said blocks having central ribs, the ends of said blocks being normally spaced apart, said ribs being adapted to receive a wire therebetween for supporting the same, said blocks being pivotally mounted upon said fingers whereby when undue pressure is exerted upon the wire carried by said ribs the ends of said blocks will be swung into a binding engagement with the wire for positively holding the same from slipping.
- 20 8. An insulator of the class described, comprising a frame, said frame comprising base arms, fingers extending from said arms, means for supporting said frame, blocks positioned upon said frame, said blocks having channels, said fingers resting within said channels, said blocks having central ribs, the ends of said blocks being normally spaced apart, said ribs being adapted to receive a wire therebetween for supporting the same, said blocks being pivotally mounted upon said fingers whereby when undue pressure is exerted upon the wire carried by said ribs the ends of said blocks will be swung into a binding engagement with the wire for positively holding the same from slipping.
- 25 9. An insulator of the class described, comprising a frame, said frame comprising base arms, fingers extending from said arms, a screw extending from said frame for supporting
